UNITED STATES PATENT OFFICE.

GEORGE G. WILEY, OF CHICAGO, ILLINOIS, ASSIGNOR TO STREETER-AMET WEIGHING & RECORDING COMPANY, OF CHICAGO, ILLINOIS, A CORPORATION OF ILLINOIS.

SWING-SASH LATCHING FIXTURE.

Application filed August 15, 1924. Serial No. 732,161.

This invention has for its object to provide a device adapted for attachment to hinge doors, windows and the like for firmly latching the same in closed or in open positions 5 as desired without rattle resulting from gusts of wind when in said open positions.

A further object of the invention is to provide a device of the character aforesaid which is small, compact, light, cheap and 10 easy to manufacture and install and which is so constructed and arranged with respect to installation as to be capable of bearing all strains and stresses to which it is liable to be subjected without requiring that it be 15 made of heavy materials and secured in place by numerous or very long or large screws or the like.

The preferred embodiment of the invention is illustrated in the accompanying drawings 20 wherein:—

Fig. 1 is a fragmentary elevation of a window-sash and its casing equipped with a fixture constructed in accordance with the invention.

Fig. 2 is a plan section on the line 2—2 of Fig. 1.

Figs. 3, 4 and 5 are perspective views of three component parts of the portion of the fixture adapted to be mounted on the window-casing or door frame.

The device is particularly adapted for hinged or so-called "French" windows which swing outwardly from their frames and are, therefore, particularly subject to being buffeted by the wind. Numerous fixtures adapted for firmly holding windows of this type in desired open positions are now on the market, the majority thereof being objectionable because they must be mounted on the window-sills in order to be accessible, or because they rattle under the influence of wind-pressures on the windows when open, or for other reasons, including particularly the objection of high cost and difficult installation.

The device of this invention is designed to overcome all of the objections which have mitigated against the use of fixtures intended for the same general purposes, primarily 59 by (a) enabling it to be installed at the top of the window and its casing while operable from an easily accessible elevation; (b) rendering it very compact and capable of being easily installed by unskilled persons; (c)

obviating possibility of rattle, and generally 55 rendering the same practical for use.

The device comprises a wall-plate 1 having a relatively long flat upper flange 2 and a shorter flat, lower flange 3, the plate 1 being adapted to be secured to a side of the 60 window-casing or door-frame adjacent the top thereof. In said flanges 2 and 3 there are provided two vertically aligned, transverse slots 4 and 5, respectively, the former being 65 of greater length than the latter.

Associated with said flanges 2 and 3 is a plate 6 having an offset end-portion 7 and a flange 8, the latter terminating in a tongue 9 and projection 10. The tongue 9 is adapted to be received in and snugly fit the slot 4 70 and the projection 10 to pass through and snugly fit the slot 5, the length of the tongue 9 being exactly equal to the distance separating the upper surfaces of the flanges 2 and 3 so that the shoulders 11 and 12 will rest 75 upon said flanges 2 and 3 when the projection 10 is passed through the slot 5. The said projection 10 is of greater length than the thickness of the flange 3 so that it will project below the same, the projecting end portion being upset like a rivet (as indicated by reference character 11^a) to permanently 80 secure the plate 6 to said flanges 2 and 3.

When thus secured, the plate 6 will be spaced from and extend parallel with the 85 flange 2 and project beyond the outer end of the latter, the offset end-portion 7 thereof being provided with a perforation 12^a to receive a fastening screw or the like to enter the top wall of the window-casing or door-frame and serving to space the plate 6 therefrom.

The plate 6 is provided between its ends with a perforation 13 which is disposed in vertical alignment with a similar perforation 95 14 in the outer end portion of the flange 2, said perforations 13 and 14 being adapted to receive the pivot-element 15 for the flat circular plate 16 provided with the integral radial arm 17, said plate having a series of 100 perforations 18 arranged at regular intervals equidistantly from the axis of the perforation 19 in the center thereof through which the pivot element 15 (preferably a rivet) passes. One of said perforations 18 is 105 disposed diametrically opposite the arm 17 and the remaining perforations 18 are disposed in equal number to the right and left

thereof so that, in assembling the fixture it will be capable of installation at either the right or left side of the window casing or door-frame.

5 In the flange 2, between the slot 4 and opening 14, there is a perforation 20 and in the outer end of the flange 3, a perforation 21 vertically aligned with the perforation 20. A latch bolt 22 having a slightly tapered 10 upper end-portion to engage in the perforations 18, is mounted for reciprocation in said perforations 20 and 21. Said latch-bolt 22 is provided adjacent its upper end with a cross-head or similar stop formation for limiting its upward movement and for engaging 15 the upper end of the helical compression spring 24 which surrounds said latch bolt and bears at its lower end upon the flange 3 to thus hold said latch-bolt normally at the 20 upper limit of its movement. The diameter of the perforations 18 is slightly less than that of the body of the latch-bolt 22 so that the tapered upper end of the latter will snugly engage therein before the said latch-bolt has attained the upper limit of its movement as determined by the cross-head 23. Preferably, the plate 6 is provided with a 25 perforation 25 vertically aligned with the perforations 20 and 21 and of larger diameter than the extreme upper end of the latch bolt so that the latter may project above the plate 16 and into said perforation 25. Secured to the lower end of the latch-bolt 22 is a pull chain 26 for operating the same 30 against the action of said spring 24, the length of the latter, when completely collapsed, being such that it constitutes a stop for limiting the downward stroke of the latch-bolt to a point at which its extreme 35 upper end is disposed below the plate 16 but above the lower face of the flange 2. The depth of the flange 8 of the plate 6 is such as to space the latter from the flange 2 a distance only slightly greater than the 40 thickness of the plate 6.

45 Mounted on the upper rail of the window or door-sash is an L-shaped guide plate 27 having perforations for the passage of fastening screws 28, in one arm and a slot of somewhat greater length than the width of the arm 17 of plate 6 in the outer end portion of its other arm. The position of said slot 29 is such that its outer end wall contacts with the outer edge of the arm 17 when the latter is disposed parallel with the sash and is spaced from the latter a distance slightly in excess of the length of the radius of the plate 16. A flat spring 30 having perforations adapted for alignment with those 50 of the L-shaped guide-plate 27 through which the screws 28 pass and having an ogee curved end portion 31 bearing at its free end portion on the inner edge of the arm 17 adjacent its point of engagement in the slot 55 29, is secured in place by the said screws 28.

The operation of the device will be readily understood from the drawings and foregoing description without further recitation.

Installation of the fixture requires only that the guide-plate 27 shall be so disposed as to permit the sash to be opened to the fullest extent (through an arc of a little more than ninety degrees) without effecting withdrawal of the arm 17 from the slot 29. It is therefore disposed a predetermined distance from the side wall of the casing to which the plate 1 is attached and its elevation determined by the position of the latter on said casing. The elevation of the plate 1 is determined by the offset end-portion 7 of the plate 6. The spacing of the plate 1 from the inner face of the sash is determined by the guide-plate 27. The person installing the fixture is thus easily guided and instructed in effecting such installation.

90 The fastening screw passing through the perforation 12 cooperates with the fastening screws for the plate 1 to readily transmit all stresses and strains on the fixture to the window casing at such widely separated points as to place no great strains on said screws. This permits the device to be made of small dimensions so that it presents a very neat appearance and, being disposed in an upper corner of the casing, is usually hidden from view by draperies. It presents no disadvantages either from the standpoint of cutting off light, window-sill area, interference with draping, difficulty of installation or operation or rattling, the spring 30 and snug fits of operating elements obviating lost motions usually responsible for such rattling.

95 Obviously, the device is adapted only for outwardly swinging windows and doors and is adapted for the type of window which swings on a horizontal axis similarly to transoms. Long life is further assured by having the pivot element 15 rigidly supported at both ends to thus relieve it of tortional strains and stresses tending to loosen it.

100 I claim as my invention:—

1. A swing-sash fixture including a wall-bracket adapted to be secured to a side-wall and the top wall of a window or door-casing at relatively widely separated points, a member pivotally secured at one end to said bracket between the points of its attachment to the casing, the pivotal axis of said member being substantially aligned with the points of attachment of the bracket to the casing, a spring-controlled latch element on said bracket normally interengaging therewith and selectively engaging with said member for holding the latter in predetermined positions relatively to the former, and means operatively engaging said member with the sash to thereby hold the latter in predetermined positions relatively to the casing.

115 2. A swing sash fixture including a wall-

bracket adapted to be secured to a side wall of a casing and presenting a plurality of outwardly extending arms disposed parallel with each other and with the top wall of the casing, a member operatively connected with the sash and pivotally engaged at one end to and having its pivoted end arranged between two of said arms, said member provided with formations for engaging a latch-bolt, and a manually releasable, spring-held latch bolt reciprocably mounted in said bracket normally in engagement with the two said arms and for selective engagement in said formations of said member for retaining the latter in set position.

3. A swing-sash fixture including a wall bracket adapted to be secured to a side-wall and the top wall of a window or door-casing at relatively widely separated points and presenting a plurality of outwardly extending arms disposed parallel with each other and with the top wall of the casing, a sash setting member operatively engaged with the sash and pivotally engaged at one end with two of said arms between the points of attachment thereof to the top and side wall of the casing, said member provided with formations for engaging a latch-bolt, and a manually releasable, spring-held latch bolt reciprocably mounted in said bracket and normally engaged with the two said arms and for selective engagement in said formations of said member for retaining the latter in set position.

35 4. A swing-sash fixture including a wall bracket adapted for attachment to two relatively perpendicularly disposed walls of a casing at widely separated points, said bracket including three arms disposed parallel with each other and perpendicularly to the hinge-axis of a sash, a member operatively engaged with the sash and disposed at one end between and pivotally associated with two of the arms of the bracket, said member equipped with latch-formations for locking it in any one of several predetermined positions within the limits of its pivotal movement relatively to the bracket, and a manually releasable spring-held latch element operatively associated with the third arm and one of the arms of the bracket with which the said member is pivotally associated for engaging said formations of the latter.

55 5. A swing-sash fixture including a wall bracket adapted for attachment to two relatively perpendicularly disposed walls of a casing at widely separated points, said bracket including three arms disposed parallel with each other and perpendicularly to the hinge-axis of a sash, a member operatively engaged with the sash and disposed at one end between and pivotally associated with two of the arms of the bracket between the points of attachment of said bracket

with the several walls of the casing, said member equipped with latch-formations for locking it in any one of several predetermined positions within the limits of its pivotal movement relatively to the bracket, and a manually releasable, spring-held latch element operatively associated with the third arm and one of the arms of the bracket with which the said member is pivotally associated for engaging said formations of the latter.

6. In a swing-sash fixture, a wall bracket comprising a wall plate having parallel, flat end flanges extending perpendicularly thereto, there being transverse slots in said flanges, and a plate having an end flange extending perpendicularly thereto and terminating in a narrower end portion extending through the said slots and having its extreme end upset to provide a shoulder to engage the face of one flange of said wall-plate there being shoulders bordering the inner end of the narrower portion of said flange for engaging an opposed surface of the other flange of said wall-plate to thereby permanently couple said plates, and a member slidably engaged at one end with the window-sash and pivotally engaged at its other end with and disposed between said plate and said wall-plate.

7. In a swing-sash fixture, a wall bracket comprising a wall plate having parallel, flat end-flanges extending perpendicularly thereto, there being transverse slots of respectively different lengths in said flanges, and a plate having an end flange extending perpendicularly thereto and terminating in a tongue of less width than said flange and snugly fitting the longer of said slots, passing through the latter and terminating in a projection snugly fitting and passing through the shorter slot and having its extreme end upset to thereby permanently couple said plates, and a member slidably engaged at one end with the window-sash and pivotally engaged at its other end with and disposed between said plate and said wall-plate.

8. A swing-sash fixture including a wall bracket comprising a plate adapted to be secured to a wall of a casing and having perpendicular end flanges of respectively different lengths, and an arm rigid and parallel with the longer flange and extending from between the ends thereof to a point beyond its free end, the outer end of said arm including a perforated offset portion adapted to be secured to a casing wall extending perpendicularly to the wall to which said plate is adapted to be secured, and a member slidably engaged at one end with the window-sash and pivotally engaged at its other end with and disposed between said plate and said wall-plate.

9. A swing-sash fixture including a wall

4

bracket comprising a plate adapted to be secured to a wall of a casing and having perpendicular end flanges of respectively different lengths, and an arm rigid and parallel with the longer flange and extending from between the ends thereof to a point beyond its free end, the outer end of said arm including a perforated offset portion adapted to be secured to a casing wall extending perpendicularly to the wall to which said plate is adapted to be secured, and a member adapted to be operatively associated with the sash pivotally secured at one end to said arm and said longer flange.

10 10. A swing-sash fixture including a wall bracket comprising a plate adapted to be secured to a wall of a casing and having perpendicular end flanges of respectively different lengths, and an arm rigid and parallel with and secured to both said flanges and extending from a point between the ends of the longer flange to a point beyond its free end, the outer end of said arm including a perforated offset portion adapted

20 25 to be secured to a casing wall extending perpendicularly to the wall to which said plate is adapted to be secured, and a member slidably engaged at one end with the window-sash and pivotally engaged at its other end with and disposed between said plate and said wall-plate.

11. A swing-sash fixture including a wall bracket comprising a plate adapted to be secured to a wall of a casing and having perpendicular end flanges of respectively different lengths, and an arm rigid and parallel with and secured to both said flanges and extending from a point between the ends of the longer flange to a point beyond its free end, the outer end of said arm including a perforated offset portion adapted to be secured to a casing wall extending perpendicularly to the wall to which said plate is adapted to be secured and a member adapted to be operatively associated with the sash pivotally secured at one end to said arm and said longer flange.

12. A swing-sash fixture including a wall bracket having a plurality of parallel arms and adapted to be secured to two relatively perpendicular walls of a casing at widely separated points, a member having sliding

engagement with the sash pivotally secured at one end to two arms of said bracket and being equipped with formations equally spaced from its pivotal axis for engaging latching means, and a manually releasable, spring-held latch element associated with two of the arms of said bracket for engagement in said formations of said member for holding the latter in predetermined positions in its pivotal movement.

13. A swing-sash fixture including a wall bracket having a plurality of parallel arms and adapted to be secured to two relatively perpendicular walls of a casing at widely separated points, a member pivotally secured at one end to two arms of said bracket and being equipped with formations equally spaced from its pivotal axis for engaging latching means, and a manually releasable, spring-held latch element associated with two of the arms of said bracket for engagement in said formations of said member holding the latter in predetermined positions in its pivotal movement and a bracket secured to the sash and having sliding engagement with said member, and a spring operatively associated with said last-named bracket and said member for resisting relative movement thereof.

14. A swing-sash fixture including a wall bracket having a plurality of parallel arms and adapted to be secured to two relatively perpendicular walls of a casing at widely separated points, a member pivotally secured at one end to two arms of said bracket and being equipped with formations equally spaced from its pivotal axis for engaging latching means, and a manually releasable, spring-held latch element associated with two of the arms of said bracket for engagement in said formations of said member for holding the latter in predetermined positions in its pivotal movement and a bracket secured to the sash and having sliding engagement with said member, a bracket mounted on the sash and provided with a slot, an arm on said member slidable in said slot, and a spring on said last named bracket bearing on said arm to resist movement thereof laterally of said slot.

GEORGE G. WILEY.
